UNITED STATES PATENT OFFICE.

FRANCES A. SCHAEFER, OF NEW YORK, N. Y., ASSIGNOR TO JAMES R. KEISER, OF BROOKLYN, NEW YORK.

DESIGN FOR A STOCK.

SPECIFICATION forming part of Design No. 35,545, dated December 31, 1901.

Application filed August 20, 1901. Serial No. 72,709. Term of patent 3½ years.

To all whom it may concern:

Be it known that I, FRANCES A. SCHAEFER, a citizen of the United States, and a resident of the borough of Manhattan, city, county, and State of New York, have invented and produced a certain new and original Design for a Stock, of which the following is a specification, reference being had to the accompanying drawing, in which the figure is a perspective view of a stock embodying my design.

The design in its entirety consists of a neckband A of approximately the same width throughout its length and overlaid on the out-

side by bands B B' of less width, having their front ends spaced apart and connected with each other by a lacing C.

The leading feature of the design consists of the neckband A, the bands B B', and the lacing C.

What I claim is—

The design for a stock herein shown and described.

FRANCES A. SCHAEFER.
